ARC LAMP AND CARBON GUIDE

Eric G. Pophal, St. Pauls, N. C.

Application February 19, 1944, Serial No. 523,035

1 Claim. (Cl. 176—119)

This invention relates to an improved arc lamp and especially to a novel method and apparatus for aligning the carbon elements thereof and maintaining the original alignment of the carbons while burning in the arc of such a lamp or similar projector.

More particularly, this invention embraces a high temperature resistant, high fusion point glass supporting device for the carbon elements and contemplates the use of such improved auxiliary electrode guides in order to effect a more complete, efficient and more uniform burning and consumption of the carbon elements.

In accordance with the above general description, the specific embodiment of the invention herein disclosed incorporates a pair of guides, one for each carbon element of an arc lamp, which guides are made of an efficient light transmitting material, such for example as a high melting point glass, i. e., that known by the trade-mark "Pyrex" being a preferred type although various other materials such as quartz are equally applicable.

In view of the multifarious uses to which the type of carbon guide herein below more particularly described may be adapted it is contemplated that a number of advantages will accompany its use. Although illustrated as part of a moving picture projector it is to be understood that the guides described as elements of this invention find ready and similar application for the carbon elements present in search lights, theater spot lights, medical arc lamps, suntan lamps and the like. These guides find a particularly appropriate embodiment when used with the newer type of very thin carbon element now attaining practically universal acceptance for use in projection lamps. The absence of internal structural support in such thin carbon electrodes clearly necessitates an auxiliary guide for maintaining alignment of the carbon elements.

Thus, it is a major object of this invention to provide a simple guide for aligning the carbon elements of an arc lamp.

Another object is to provide an improved support for the carbon elements whereby the alignment of such carbon electrodes is maintained fixed during operation resulting in an improved and constant light source. Still another object is to provide a carbon guide which is capable of transmitting most, if not all, of the light through its own structure thereby avoiding the appearance of shadows and poorly lighted areas on a screen on which the projected light falls.

A further object is to provide means for effecting a more economical and efficient consumption of the carbon elements. A still further object is to provide an improved lateral support for carbon electrodes whereby a uniformly white light is obtained from the carbon arc. These objects are attained by the invention and in addition a great number of advantages accompany its use, such as, for example, indirectly protecting the operator's eyes by necessitating less frequent direct observation of the burning arc, avoidance of constant burning off of irregular edges from the carbons, provision of a drip well into which the carbon ash and copper drippings fall from the burning arc thus keeping the inner surfaces of the projector and the reflector comparatively free of debris and smoke particles, to enumerate only a few of the more obvious advantages. Still other objects and advantages will become apparent or 10 will be suggested to those skilled in the art upon reading the following description of one illustrative embodiment of the invention.

In the accompanying drawing:

Figure 1 is a side view of a motion picture projection device showing in broken lines, through the case, the association of the present invention with the assembly of parts commonly found in such projectors;

Figure 2 is an enlarged view of the carbon electrode guide in operative position, the gap between the electrodes being somewhat exaggerated in order to show the reflection of the crater arc more clearly;

Figure 3 is a sectional view taken on the line 3—3 of Fig. 2; and

Figure 4 is a perspective view of the carbon electrode guide in one of its more useful forms.

Referring, now, in more detail to the drawing and more particularly to Figs. 1 and 2, the projector 10 is provided with a carbon arc type lamp as a light source. This light source comprises a lamp base 11, preferably of insulating material into which is immovably fitted a carbon electrode holder 12 and a second carbon electrode holder 13, the latter being preferably of "Pyrex" or similar high temperature resistant, light transmitting glass. Fitted into and supported by these electrode holders is a negative carbon electrode 14 and a positive carbon electrode 15, respectively. Each one of these carbon electrodes is provided with the usual carbon composition core 16 and copper outside cylindrical shell 17. This association of copper and carbon structure results in the most suitable type of white projection light giving the most intense, easily con-

trolled beam so highly desirable for non-flicker projection. The negative carbon electrode is shown projecting through opening 20' in concave reflector or mirror 20 which is supported by adjustable frame member 21. By means of wing nut and bolt 22 the reflector may be moved by sliding frame member 21 to the left or right along adjusting slot 23 so that the concave crater arc 19 formed in the end of positive carbon electrode 15 is exactly at the focus of mirror or reflector 20.

The particular structure 24 is more especially of interest in connection with the invention herein disclosed. It is a "Pyrex" or similar high temperature resistant glass support or guide for the carbon electrodes. It is constructed, in this particular embodiment, of two sloping narrow sides 24, Fig. 4, each having an extension lip 25, provided with a V-shaped or notched portion for supporting the negative electrode at 26, and a similar V-shaped or notched portion for supporting the positive electrode at 27. Since the positive electrode is usually of larger diameter, notch 27 is preferably cut correspondingly deeper than notch 26. This arrangement makes possible the exact centering of the axes of carbons 14 and 15 and the maintaining of the axes of these carbons on one and the same straight line.

As shown in Fig. 4, the glass carbon guide member has its two slanting upright carbon supporting portions 24 rigidly held together by a pair of "Pyrex" cross pieces 30 thereby forming an open top to catch the ash and copper drippings and conveying these waste products through the open end 28 for collection in removable tray 29. Such an arrangement removes most of the carbon ash and copper drippings given off by the burning arc outside of the projector and out of the field of the light beam.

The necessity for guides of some form or other can be readily appreciated particularly when carbon electrodes of such small diameter as 7 to 10 millimeters are used. Frequently, the negative carbon which almost invariably extends through a central opening, such as 20', in the reflector 20 is of the 7 millimeter size. Thus, because of the absence of the usual supporting structure found in the larger diametered positive carbon 15, the negative carbon 14 is usually the first to bend downwardly of its own weight, especially when the heat of the arc over a long period of operation weakens the thin negative carbon electrode.

Heretofore, in order to overcome this bending of the negative carbon means was provided in some cases to rotate the negative electrode slowly. This, however, made adjustment of this particular carbon electrode difficult, resulted in a flickering arc and necessitated additional servicing. Then, again, the rotating carbon frequently burned the edges off the crater 19 of the positive carbon electrode, destroying the effectiveness of the hot crater 19 and defocusing the latter. After prolonged operation, the intense heat of the arc and the heat within the projector frequently became sufficient to cause in addition, a bending of the larger positive carbon. The resultant misalignment of the carbon elements causes the crater 19 to burn irregularly and form a groove across its concave face 19; this finally forms a large overhanging lip because of the more intense burning away of one side of the crater edge. Usually this overhanging lip must be burned off by the operator before a satisfactory beam of projected light can be obtained; this wastes a

considerable portion of the carbon electrodes since during this burning off process the arc cannot be used to project a picture on a screen.

An aligned crater such as is produced by an overhanging lip on positive carbon element 15 results in a light having at least three clearly visible zones of intensity. When projected on a screen such a light field shows regions of blue, white and brown coloration or hue. It is impossible to focus a uniformly white field on the mirror 20 for subsequent projection or reflection unless a relatively perfect concave crater such as shown at 19, Fig. 2, is formed at the arcing end of positive carbon 15. Such perfect operation of the carbon arc is possible only when the carbons are held in perfect alignment. With these guides only a very small part of the total weight of each carbon electrode is supported by the electrode itself, the major portion resting upon and riding in the grooves 26, 27.

The great advantage of using a glass support is readily appreciated in the absence of shadows on the projection screen. Moreover, the use of a highly heat resistant glass enables one to use these supports within about $\frac{3}{4}$ of an inch of the hot crater 19; this assures a perfect alignment and common axial arrangement of the carbon electrodes. In addition, the hardness of such heat resistant glass lessens the clouding effect on its polished surface caused by the bombardment from the hot carbon ashes and copper particles. A typical specimen of this type of guide was used over a period of 5 to 6 months without requiring replacement because of opaqueness developed on the glass surface resulting in the formation of a shadow on the screen. It is to be noted in passing, that the mirrors themselves must be replaced occasionally because of the ground glass effect produced by the bombardment of carbon particles.

Although the gap between the rear negative and the front positive carbon electrodes is somewhat exaggerated in Fig. 2 it is to be understood that it is really about $\frac{1}{4}$ inch in the usual projection lamp and is shown larger in the drawing to facilitate the visualization of its operation and the collimation of the projected light beam.

It is to be noted that the use of guides such as those above described will not keep a white light continuously on the projection screen but these guides will keep a uniform light field projected on the screen. As the crater 19 burns farther away from the mirror 20 it gets out of the focus of mirror 20 and thus necessitates moving the carbon electrode 15 towards the mirror 20. However, the guides 24 assure a perfect crater 19 and maintain a uniform field of light projected on the screen, unspotted by areas of different hues and colors.

With the guides of this invention, the usual carbon regulating or feeding units function much more effectively since with a practically perfect crater always in operation there is little or no opportunity for a sudden change in the resistance of the arc and as a result, the usual automatic carbon feeding devices found in the better type lamps function by practically imperceptible gradations of adjustment when viewed by the results produced on the projection screen. Thus flickering is completely overcome when these guides are used. In addition, the highly useful insulating properties of glass are utilized to full advantage. Although this invention produces its most favorable results when used with the newer type of high intensity carbon lamp principally

because of the greater extremes of temperature and current strength to which the carbon elements are subjected therein, it can be advantageously used and readily adapted for incorporation in the older type of moving picture projector, spot light and search light as well as other types of service lamp.

I claim:

In an arc lamp, a casing, a concave mirror having a focal point within the casing, two carbon electrodes forming an arc at the focal point, a heat resistant transparent support maintaining the electrodes in fixed alignment and positioned to support the electrodes approximately in the vicinity of the arc.

ERIC G. POPHAL.
